UNITED STATES PATENT OFFICE.

SUMNER SHAW, OF BOSTON, MASSACHUSETTS.

SAFETY DEVICE FOR ELEVATORS.

SPECIFICATION forming part of Letters Patent No. 240,198, dated April 12, 1881.

Application filed February 5, 1881. (No model.)

To all whom it may concern:

Be it known that I, SUMNER SHAW, a citizen of the United States, residing at Boston, in the county of Suffolk and State of Massachusetts, have invented certain new and useful Improvements in Safety Devices for Elevators; and I do hereby declare that the same are fully described in the following specification and illustrated in the accompanying drawings.

This invention relates to improvements in safety devices for elevators, and it is carried out as follows, reference being had to the accompanying drawings, in which—

15 Figure 1 represents a plan view, and Fig. 2 represents a longitudinal section on the line A B, shown in Fig. 1.

Similar letters refer to similar parts wherever they occur on the different parts of the 20 drawings.

In the drawings, *a* represents the elevator-well.

b is the car, actuated by means of the wire rope *c*, which is carried over the wheel or pulley *d*, as usual.

25 *e* represents an upper beam at the top of the well *a*, and *f* represents a similar beam at its bottom, as usual.

b' is the top of the car *b*, and *b''* represents 30 the bottom or floor of said car.

From top to bottom of the well *a* extends a spirally-grooved stationary cylinder, *g*, provided with a circumferential spiral groove, *g'*, as shown. I prefer to make said spirally-grooved 35 cylinder *g* hollow and in section, as shown, and each section being made with a projection to fit into a corresponding recess on the next section, as shown at *g''* in Fig. 2, so as to prevent a rotary motion of any sectional part of the 40 spirally-grooved cylinder *g* during the up-and-down motion of the car *b*, as will be further described.

h is a central rod within the hollow cylinder *g*, which may be made also in sections, 45 united together by screw or other equivalent couplings, as may be desired. The upper and lower ends of the central rod, *h*, pass respectively through the upper and lower beams, *e* and *f*, to which it is secured by means of suitable fastening-nuts, *e'* and *f'*, as shown, by which arrangement the various hollow sec-

tions composing the spirally-grooved cylinder *g* are held rigidly together, so as to form, as it were, one solid piece. The spirally-grooved cylinder *g* passes through the car *b*, as shown, 55 perforations being for this purpose made through the top and floor thereof, as shown, the floor-perforation being made large enough to allow the hub of the nut *k* to be inserted through it without coming in contact with the 60 side of such perforation. The nut *k* is also spirally grooved and provided with a spiral projection, *k'*, fitting nicely into the corresponding spiral groove *g'* on the cylinder *g*, as shown in Fig. 2.

k'' is a flange at the lower end of the nut *k*, and *k'''* is a similar flange at the upper end of said nut.

l is an annular flange secured to the top of the floor *b''*, and *l'* is a similar annular flange 70 secured to the bottom or under side of the said floor *b''*, as shown.

The pitch of the spiral groove *g'* is so made that it will cause the nut *k* to rotate freely around the spiral cylinder *g* without much friction during the ordinary up-and-down motion of the car *b*; but in case of an accident, by the breaking of the rope or otherwise, the flange *l'* is brought in contact with the lower flange, *k''*, of the nut *k*, causing the whole weight of 80 the car *b* to rest on the said nut, by which the car is instantly brought to a standstill, as the nut *k* is prevented from turning around the spirally-grooved cylinder *g* on account of the increased frictional resistance between the 85 lower flange, *k''*, on the nut *k* and the lower flange, *l'*, on the under side of the floor *b''*.

I am aware of United States Patent No. 87,143, of 1869, in which a positively-actuated nut is caused to rotate around a stationary 90 screw-shaft, so as to raise and lower the elevator-car; but such is not my invention, as my nut is not positively actuated to raise and lower the car, but only loosely rotated around the screw-shaft by the vertical motion of the 95 car, and serving only as a safety device if the car should, from any cause, descend too rapidly, the car in my invention being raised and lowered by an independent hoisting device. I also wish to state that I do not claim a 100 continuous sectional screw-shaft, as shown in said Letters Patent; neither do I claim the partic-

ular kind of nut as shown in United States Letters Patent No. 119,731, of 1871; but

What I wish to secure by Letters Patent, and claim, is—

- 5 The herein-described safety device for elevators, consisting of the stationary spirally-grooved cylinder $g\ g'$, the loosely-rotating nut k , having upper and lower flanges, $k'''\ k''$, and the flanges $l\ l'$ on the car-floor b'' , in combi-

nation with an independent hoisting device, to as and for the purpose set forth.

In testimony whereof I have affixed my signature in presence of two witnesses.

SUMNER SHAW.
